Patented June 9, 1914.

UNITED STATES PATENT OFFICE.

FRANK LINDEEN, OF CLINTON, ILLINOIS.

FUNNEL.

1,099,706.

Specification of Letters Patent.

Patented June 9, 1914.

Application filed April 29, 1913. Serial No. 764,388.

To all whom it may concern:

Be it known that I, FRANK LINDEEN, a citizen of the United States, residing at Clinton, in the county of DeWitt and State of Illinois, have invented certain new and useful Improvements in Funnels, of which the following is a specification, reference being had therein to the accompanying drawing.

10 This invention relates to a funnel and has special reference to a funnel which is provided with a simple and efficient means for preventing the receptacle which is being filled from running over.

15 Another object of this invention is the production of a flexible neck which is used in combination with the funnel for preventing the air escaping from the receptacle which is being filled by passing around this 20 flexible neck, this flexible neck being adapted to easily bend in case the upper portion of the funnel is hit, and in this manner prevent the receptacle from overturning.

With these and other objects in view, this 25 invention consists of certain novel combinations, constructions and arrangements of parts as will be hereinafter fully described and claimed.

In the accompanying drawing: Figure 1 30 is a perspective view of the funnel showing the same positioned upon the bottle. Fig. 2 is a central vertical section of the device showing the same carried by a portion of the bottle. Fig. 3 is a central vertical section of the funnel illustrating how the same may give in case it is accidentally hit, and in this manner prevent the receptacle which is being filled from overturning. Fig. 4 is a longitudinal section taken through a rod 35 used in connection with this device. Fig. 5 is a section taken on line 5—5 of Fig. 4 looking in direction of the arrow. Fig. 6 is a section taken through a portion of a slightly modified form of a rod and lifting member.

40 Referring to the accompanying drawing by numerals it will be seen that the funnel is provided with the usual frusto-conical body 1 having a rim 2 adjacent the lower end thereof. This body 1 carries a flexible 45 neck 3 which is made of any suitable material such as rubber, which clamps or fits upon the rim 2 thereby holding the neck in position in connection with the body. When the funnel is positioned upon a receptacle to 50 be filled, this flexible neck 3 will fit snugly in the member which is being filled, and in

this manner prevent the escaping of air upon the side portions of the same. A bridge 4 is positioned upon the upper portion of the body 1 so as to extend entirely 60 across the same; the bridge being provided intermediate its ends with a large body 5. This body 5 is provided with an opening 6 through which the flexible hollow rod 7 is adapted to pass as shown in Fig. 3. This 65 flexible hollow rod 7 is provided at its upper end with the threaded portion 8 upon which a lifting ring 9 is positioned, this lifting ring 9 being held firmly in position by means of the nut 10. In this manner it will 70 be seen that the ring 9 will normally rest upon the enlarged body 5 and will prevent the hollow rod 7 from falling down to the receptacle which is being filled. This hollow rod 7 carries a conical stopper 11 upon 75 which is positioned a rubber casing or other suitable material 12 which is adapted to fit upon the lower end of the rubber neck 3 for preventing the passage of liquid therethrough.

80 When this device is used, the funnel is positioned upon the receptacle which is to be filled, as illustrated in Figs. 1 and 2. The neck 3 will fit snugly into the receptacle which is to be filled so as to prevent the passage of air between the outer portion of the neck and the inner portion of the opening formed in the receptacle. The liquid may then be poured into the body 1 until the receptacle is filled. In order to allow the filling of the bottle or other receptacle, the flexible rod 7 is formed hollow, so as to allow the air from the receptacle to pass therethrough, and out through suitable apertures 13. As soon as the receptacle is 85 filled, the liquid will enter the lower portion of the flexible hollow rod 7 whereby the air will be prevented from passing into the rod and in this manner the flow of the liquid 90 into the receptacle will be stopped. A person may then grasp the ring 9 and lift the funnel from the receptacle. If any liquid 95 happens to be in the body 1 and neck 3 when the same has been lifted from the receptacle, the member 11 will be drawn up so as to 100 allow the casing 12 to engage the lower portion of the neck 3. In this manner it will be seen that the funnel may be carried from place to place without spilling the liquid 105 contained therein. When the funnel is in 110 position upon a receptacle, if the same is hit accidentally, the neck 3 will easily bend

so as to allow the body 1 to give without danger of upsetting the receptacle.

In the form illustrated in Fig. 6 there is provided a hollow rod 14 which is open at its upper end, as illustrated at 15. This rod 14 is provided with the usual threaded portion 8', nut 10 and lifting ring 9. In this form it will be seen that the air can escape through the portion 15 while the ring 9 will 10 form an efficient means for preventing any foreign object or dirt from passing or falling into the interior of the rod. It will also be seen that the openings 13 and 13' are so positioned under the ring 9 so as to be 15 shielded from any dirt which might pass into the rod 7 and thereby clog the passage.

From the foregoing description it will be seen that a simple and efficient funnel has been produced which will efficiently stop 20 the flow of the liquid into the receptacle which is being filled, so as to allow the liquid to come into engagement with the rod 7 and thereby cutting off the air passage, and is

also provided with a simple means for supporting the device upon a receptacle without danger of the same being overturned. 25

Having thus described the invention, what is claimed as new, is:—

A funnel comprising a body portion, a flexible neck extending from the lower end 30 of the body and adapted to engage the neck of a bottle to permit lateral movement of the body relative to the bottle, a supporting bar extending across the top of the body, a flexible air-conducting tube extending through 35 the body and neck and slidably through the supporting bar, a finger grip carried by the upper end of the tube, and a stopper carried by the lower end of the tube for sealing the neck. 40

In testimony whereof I hereunto affix my signature in presence of two witnesses.

FRANK LINDEEN
